UNITED STATES PATENT OFFICE

OLIVER B. JEFFREYS, OF OUTWOOD, KENTUCKY

CALENDAR

Application filed October 13, 1932. Serial No. 637,634.

This invention relates to improvements in calendars and pertains particularly to a calendar which is designed to be used over a number of years.

5 The primary object of the present invention is to provide a calendar which is so designed that by the turning of one element thereof a complete month may be changed.

Another object of the invention is to provide a calendar structure which employs a plurality of ribbons which are rolled upon a common carrier and are adapted to be drawn therefrom onto an individual roll, which individual rolls are so arranged that 15 a portion of each strip with a transverse series of numbers thereon may be exposed so that each of five of the six strips of the calendar will show a transverse row of numerals which coact with the numerals of the other 20 strips to give a complete calendar for one month.

Another object of the invention is to provide a calendar of the character above described which may be constructed in a cabinet of any desired size for use upon a desk or in a similar location.

The invention will be best understood from a consideration of the following detailed description taken in connection with the accompanying drawings forming part of this specification, with the understanding, however, that the invention is not confined to any strict conformity with the showing of the drawings but may be changed or modified so long 35 as such changes or modifications mark no material departure from the salient features of the invention as expressed in the appended claims.

In the drawings:—

40 Figure 1 is a view in vertical front to rear section of a calendar constructed in accordance with the present invention;

Figure 2 is a view of the face of the calendar;

45 Figure 3 is a sectional view taken substantially upon the line 3—3 of Figure 2;

Figure 4 is a view in detail of the method employed for attaching one of the numeral carrying ribbons or tapes to an individual 50 roller;

Figure 5 is a view partly in elevation and partly in section of the roll which is common to all of the numeral strips showing the manner in which the same are attached thereto and also showing the resilient means for maintaining the strips tight; 55

Figures 6 to 11 inclusive show in plan portions of the numeral strips and the month and year strip, showing the complete numeral arrangement upon five of the strips for a calendar year. 60

Figure 12 is a sectional view through the knob 22 and a portion of the adjacent cabinet wall 3.

Referring now more particularly to the drawings wherein like numerals of reference indicate corresponding parts throughout the several views, the numeral 1 indicates generally a casing for the calendar embodying the present invention. While the particular construction illustrated may be changed in minor details the preferred form is as shown wherein there is provided the back, side and bottom walls 2, 3 and 4 respectively with the relatively narrow top and front walls 5 and 6 respectively between which is positioned the inclined wall 7 which may be described as a continuation of the front wall at a rearward inclination. This wall 7 will be referred to as the face of the calendar and as shown it is hinged or otherwise suitably secured as indicated at 8 to the forward end of the top wall 5 so that it may be raised for access to the interior of the cabinet. The wall structure 7 is provided with the two window openings 9 and 10 which have the glass panels 11 and 12 respectively therein. 75 80 85

Within the cabinet are bearing strips 13 secured along the inner faces of the side walls 3 directly beneath and parallel with the face or hinged wall 7 and each of these strips is provided with five bearing notches 14 which are located beneath the window glass 12 and a sixth bearing notch 15 which is located beneath the window glass 11. 90 95

Disposed transversely of the cabinet beneath the window glass 12 are five rollers each of which is indicated by the numeral 16 and each of these rollers has a shaft extending longitudinally therethrough as indicated 100

at 17 and projecting beyond the ends to form supporting trunnions each of which positions in a bearing recess or notch 14. Beneath the window 11 is a roll 18 similar to the rolls 16 which also has a shaft 19 therethrough which at one end projects to form the trunnion 20 while at its other end it is elongated as indicated at 21 to extend through the adjacent side wall of the cabinet to receive outside of the cabinet the knurled head 22.

Upon one side of the cabinet each of the roller trunnions has secured thereto a sprocket wheel 23 and these are all connected together for unitary rotation by the sprocket chain 24.

Beneath the rollers 16-18 there is mounted in the cabinet between the side walls thereof the relatively large roll or cylinder 25 which is supported upon a shaft 26, the end portions of which project beyond the ends of the roller to form the trunnions 27 which are suitably mounted in the adjacent side walls of the cabinet. The roll or cylinder 25 turns freely upon the shaft 26 and within the cylinder is a coil spring 28 which surrounds the shaft 26 and at one end is secured thereto as indicated at 29 while at its other end it is secured to the cylinder as indicated at 30. This spring normally tends to rotate the cylinder in one direction to a stationary position as will be hereinafter more fully described.

Within the cabinet are six strips of paper or other suitable material which are indicated by the numerals 31 to 36 inclusive and each of these strips at one end is provided with an aperture 37 so that it may be secured to the cylinder 25 in the manner shown in Figure 5. One of these strips, as for example the strip 31, is divided into a number of areas 38 in each of which is arranged in a line longitudinally of the strip the names of the twelve months of the year and beside each month the year number as shown in Figure 6. Each of the other strips 32 to 36 inclusive is likewise divided into a series of areas which are indicated by the numerals 39 and each of these areas is divided into twelve transverse rows of numerals. The strip 32 is provided with the necessary numerals for the first transverse line of each calendar month and the strips 33, 34, 35 and 36 carry the numerals for the second, third, fourth and fifth lines respectively of each monthly calendar.

As previously stated the strips are each secured at one end to the cylinder 25 and each is secured at its other end to an individual one of the rollers disposed beneath the windows in the front of the cabinet. The strip 31 has its free end provided with an aperture 40 in which is engaged a hook 41 upon the roll 18 and each of the other strips has a similar aperture at its free end which is indicated by the numeral 42 which engages a hook 43 upon one of the five rolls 16.

In arranging the strips upon the cylinder

the first strip 31 is attached and connected with the roll 18 and the other strips are attached in the order in which they are shown in the figures so that the strip 32 has its free end connected with the uppermost one of the rolls 16 and the others are connected in the proper order to the underlying rolls so that when the calendar is in use the top strip will show the name of a month and a year through the window opening 9 and the other strips will each show a row of numerals given in the proper order for that particular month. From the foregoing description it will be readily apparent that with a calendar constructed in accordance with the present invention a single turn of the knob 22 will at once shift all of the strips so as to move the proper name and numerals in place of any desired month and by providing the strips in suitable lengths with the necessary groups of numerals thereon the calendar may be made for service over a number of years.

While the structure herein shown and described employs a sprocket chain for connecting the six rolls it is to be understood that these rolls may be connected by ears or in any other suitable manner, if desired. It is also to be understood that the numeral bearing strips may, if desired, be drawn over suitable supporting bars or tables disposed beneath the window glasses so that a portion of each strip will lie flat or parallel with the glass instead of being rounded as in the present case where the strip passes over a roller.

In order to hold the spring controlled roller to prevent the same rewinding the strips thereon from the smaller rollers 18 the knob 22 is formed as shown in Figure 12 to provide a chamber 44 and access is had to this chamber through the outer end of the knob which is closed by the threaded plug 45. This plug has a central opening 46 therethrough which is of polygonal outline to receive the similarly formed end portion 47 of the shaft 21. The inner end of the knob 22 is provided with a similar opening as shown in Figure 12. Within the chamber 44 is a coil spring 48 which surrounds the adjacent end of the shaft, bearing at one end upon the inner end of the chamber wall while at its other end it is secured to the end 47 of the shaft so that it normally tends through its tendency to expand, to force the knob inwardly so that the notches 49 in the inner end will engage the lugs or ears 50 upon the adjacent side of the cabinet wall 3. By pulling the head or knob 22 outwardly to disengage the lugs from the notches 49 the spring 48 will be compressed and the shaft 21 may be rotated so as to wind the tapes onto the rollers 16 and 18.

The calendar may be made in any suitable size and as will be readily appreciated it is particularly adaptable for use upon a desk or in any other location where it is desired

to keep the dates of the days of the current month in view.

By providing the cylinder roll with the control spring shown the tapes will be maintained tight or under tension at all times due to the tendency of the spring to reversely rotate the cylinder to draw the tapes back thereon. The spring is located under tension as the tapes are drawn off of the cylinder onto the smaller rollers.

Having thus described the invention, what is claimed is:

1. A calendar, comprising a plurality of tapes, a cylinder common to and on which said tapes are rolled, a plurality of rollers each having an end of a tape connected thereto to be rolled thereon from the cylinder, and means for simultaneously rotating the rollers to roll the tapes thereon from the cylinder, one of said tapes having the names of the months printed thereon and a year date associated with each name and the other tapes having a plurality of transverse rows of numerals which are coordinated to give with each month the proper day dates therefor.

2. A calendar, comprising a casing having a wall provided with window openings, a cylinder rotatably mounted within the casing, a plurality of rollers arranged in the same plane within the casing adjacent said windows, some of said rollers being viewable as a group through one window and a single roller being viewable through another window, means for rotating said rollers in unison, and a plurality of tapes each connected at one end with said cylinder to be rolled thereon and having its other end connected with one of said rollers whereby each will be wrapped about a roller when the latter is turned, that tape engaging the said one roller having the months of the year and a year date printed thereon and the remaining tapes having a plurality of transverse rows of numerals which are coordinated to give with the exposure of each month name the proper day dates therefor.

3. A calendar, comprising a casing having a wall provided with window openings, a cylinder rotatably mounted within the casing, a plurality of rollers arranged in the same plane within the casing adjacent said windows, some of said rollers being viewable as a group through one window and a single roller being viewable through another window, gear elements associated with said rollers, means connecting said gear elements together for unitary operation, means exterior to the casing for rotating one of said rollers, and a plurality of tapes each connected at one end with said cylinder to be rolled thereon and having its other end connected with one of said rollers whereby each will be wrapped about a roller when the latter is turned, that tape engaging the said one roller having the months of the year and a year date

printed thereon and the remaining tapes having a plurality of transverse rows of numerals which are coordinated to give with the exposure of each month name the proper day dates therefor.

4. A calendar, comprising a casing having a wall provided with window openings, a cylinder rotatably mounted within the casing, a plurality of rollers arranged in the same plane within the casing adjacent said windows, some of said rollers being viewable as a group through one window and a single roller being viewable through another window, gear elements associated with said rollers, means connecting said gear elements together for unitary operation, means exterior to the casing for rotating one of said rollers, resilient means for maintaining the tapes in tight condition, and a plurality of tapes each connected at one end with said cylinder to be rolled thereon and having its other end connected with one of said rollers whereby each will be wrapped about a roller when the latter is turned, that tape engaging the said one roller having the months of the year and a year date printed thereon and the remaining tapes having a plurality of transverse rows of numerals which are coordinated to give with the exposure of each month name the proper day dates therefor.

In testimony whereof I hereunto affix my signature.

OLIVER B. JEFFREYS.
